LASTING-MACHINE.

1,358,127.

Specification of Letters Patent.

Patented Nov. 9, 1920.

Application filed October 12, 1916. Serial No. 125,271.

To all whom it may concern:

Be it known that I, EVERETT W. VARNEY, a citizen of the United States, residing at Newton, in the county of Middlesex and State of Massachusetts, have invented certain Improvements in Lasting-Machines, of which the following description, in connection with the accompanying drawings, is a specification, like reference characters on the drawings indicating like parts in the several figures.

This invention relates to lasting machines and particularly to toe lasting mechanism and has for its object to increase the capacity 15 and improve and simplify the construction of mechanisms for lasting the toes of shoes on right and left crooked lasts.

For many styles of shoes right and left wipers must be provided to fit the different 20 contours of the toe portion of the lasts for the right and left feet. It has previously been proposed to equip the toe lasting mechanism with two pairs of toe embracing wipers and mount the head for adjustment, as, for 25 example, for rotation to bring either pair of wipers into position to operate on a shoe. It has also been proposed to provide an end lasting mechanism with two pairs of end embracing wipers superposed one pair above 30 the other, with means for bringing either pair into operative position for lasting a shoe toe, one pair being shaped to fit a right shoe toe and the other shaped to fit a left shoe toe. Neither of these constructions, 35 however, has come into general use partly at least because of the bulkiness or complications of such mechanism, and the practice is still followed almost entirely of taking out one pair of wipers and substituting a pair 40 adapted for the other foot when changing from right or left shoes. This changing of wipers makes it necessary to last first a series of shoes for one foot and then the mates to those shoes, it being impracticable, except 45 on sample work, to take time to change wipers and last mates alternately, although obviously the best results are obtained by lasting mates successively and matching them.

An important feature of the present invention consists in end lasting mechanism comprising two pairs of end embracing wipers arranged side by side substantially in the

same horizontal plane and movable transversely of the shoe to bring either pair into 55 operative position with operating mechanism by which either pair can be used.

Another feature of the invention consists in operating mechanism for either of the two pairs of wipers which is so arranged that 60 movement of the operating lever beyond its normal movement for opening the wipers will unlock the moving slide which carries the wipers and enable the pair which is in use to be moved out of operative position 65 and the pair which is out of operative position into position for use.

These and other features of the invention will appear more fully from the following 70 description when read in connection with the accompanying drawings and will be pointed out in the claims.

Figure 1 is a perspective view showing the head of a bed lasting machine equipped with 75 this invention;

Fig. 2 is a section on the line 2—2 of Fig. 3;

Fig. 3 is a perspective view, partly in section, showing in detail the manner of connecting the wipers to their operating mechanism.

In the drawings the toe portion of a right shoe is represented as supported on a toe rest 2 and held down upon it by a hold-down 4, a pair or set of wiper plates 6, 8 being shown as holding the upper in lasted position 85 upon the feather of the innersole of the shoe toe. The wipers 6, 8 may be of usual construction, and are shown as detachably held in carriers 10, 12 which are guided for forward and closing movement by roll studs 14, 90 16 mounted between upper and lower plates 18, 20 spaced apart by blocks 22 to which they are secured and forming with the blocks a wiper transferring slide. The transferring slide is mounted for sliding movement transversely of the shoe in a member 24 which extends forwardly above the plate 18 and beneath the plate 20. The plate 18 has a groove 26 which is engaged by a rib 28 on the member 24 to guide the slide in its transverse movement. The member 24 has a cylindrical portion 30 which is arranged to be tilted transversely of the shoe by a screw 34 in the usual manner, the longitudinal tilting of the plates being provided for as usual by 100 a screw 32.

75

80

95

105

An operating rod 36 is connected to a lever 38 by which it is moved longitudinally through the cylindrical portion 30 of the member 24 and at its forward end is arranged for operative connection with the wiper carriers 10, 12. As shown in Fig. 3 the forward end portion of the rod 36 has notches which are engaged by a fork 40 formed on or connected to a cross head 42 which is mounted for movement longitudinally of the shoe being guided by a rib 44 which engages a groove formed in the lower face of the plate 18. The wiper carrier 10 is connected by a link 46 to one end of the cross head 42 and the wiper carrier 12 is similarly connected to the other end of the cross head.

Obviously, longitudinal movement of the rod 36 by the lever 38 will move the cross head 42 in the direction of the rib 44 and cause the wiper carriers 10, 12 to advance and close the wipers 6, 8.

It will be observed that the wiper transferring slide has sufficient lateral extent to accommodate a second pair of wiper carriers 50, 52 with their accompanying wipers 56, 58, which may be the wipers for a left shoe which is a mate for the right shoe for lasting which the wipers 6, 8 are adapted.

The mechanism for operating the wipers 56, 58 is substantially identical with that for operating the wipers 6, 8, except that a fork 60 corresponding to the fork 40 is arranged with its opening directed oppositely to that of the fork 40 so that when the wiper transferring slide is moved in the member 24 transversely of the machine the fork 60 will engage the notches in the rod 36 and the wipers 56, 58 may then be operated by the rod 36 in the same manner as the wipers 6, 8, when the transferring slide is adjusted as shown in Fig. 1.

To lock the transferring slide from movement while either pair of wipers is being operated, there is provided in each of the cross heads 42 a pin 62 which extends through a slot in the plate 20 of the slide and engages a groove 64 in the portion of the member 24 which extends forwardly under the plate 20. The groove 64 extends longitudinally of the shoe to permit operative movement of the cross head relatively to the member 24, and from the groove 64 lateral grooves 68 extend transversely of the direction of operative wiper movements, the outer end portions of the grooves 68 being bell mouthed to enable the pin 62 of the cross head 42 which is in inoperative position to find the slot when it is moved to operative position even though the wipers have, by accident or intention, been partly or wholly closed while in inoperative position. It is desirable to hold the wiper transferring slide locked against transverse movement until intentionally released by the operator. To unlock

the slide, in the construction described, it is only necessary to move the lever 38 to the rearward limit of its movement, thereby bringing the pin 62 of the cross head which is in operative position opposite the opening 70 of the transverse groove 68 in the member 24, and to prevent unintentional movement of the lever 38 to such rearward limit and hold either set of wipers normally locked in operative position, a spring pin 70 is provided on the usual lever locking segment 72. When the operator desires to unlock the wiper transferring slide he moves the lever 38 far enough to compress the spring behind the pin 70, thereby bringing the pin 62 opposite the opening of the transverse groove 68 in the member 24. The slide can then be moved to bring the pin 62 on the other cross head 42 into alignment with the groove 64 which it will enter and where it will normally remain when the lever 38 is released. On the opposite ends of the slide, stops 74 are provided which so limit movement of the slide in either direction that when at either limit one or the other of the pins 62 will be 80 in alignment with the groove 64.

The movement of the lever 38 against the spring pin 70 is so limited that the lever 38 cannot be moved rearwardly beyond the position where the notches in the end portion 95 of the rod 36 will be in alignment with the forks 40 and 60 as the slide is moved to bring either of them into engagement with the notches in the rod, the forks being, of course, always set automatically in their rearward 100 position by the action of the grooves 68 on the pins 62.

In the construction described it will be seen that very convenient means is provided for adjusting the machine for lasting either 105 right or left shoes, the adjustment being made without the necessity of manipulating any additional or awkwardly placed levers and without consuming any material amount of the operator's time and also that, 110 since both sets of wipers are in the same plane, the vertical position of the toe lasting head, which is, as usual, controlled by a foot treadle, is the same for one set of wipers as for the other. It is therefore practicable 115 with this machine to last shoes in pairs, the right and left alternately.

Having fully described my invention, what I claim as new and desire to secure by United States Letters Patent is:—

1. A right and left toe lasting mechanism having, in combination, two complete pairs of toe embracing wipers arranged in substantial parallelism, one pair having an edge contour adapted to the toe of the shoe for 125 one foot, and the other pair having a different edge contour adapted to the toe of the shoe for the other foot, means for mounting said pairs of wipers for movement, while in parallel relation, transversely of the shoe to 130

enable one pair to be moved out of operative position and the other pair to be moved into operative position, and means for operating said pairs of wipers to do their work.

5 2. An end lasting mechanism having, in combination, two pairs of similarly facing end embracing wipers arranged in substantial parallelism, each having an edge contour adapted to wipe an upper into lasted position over the last, one pair of wipers having a shape differing from that for which the other pair of wipers is adapted, means for mounting the wipers so that either pair may be moved into operative position with relation to a shoe in the machine, and operating mechanism by which either pair of wipers may be used alternatively.

20 3. An end lasting mechanism having, in combination, two complete sets of toe embracing wipers arranged side by side, one set having a different edge contour from the other to adapt it to embrace and snugly fit a shape different from the shape which the other fits, and operating means common to 25 said wipers arranged to impart to one set of plates toe embracing movements while the other set of wipers remains at rest.

30 4. A right and left end lasting mechanism having, in combination, two pairs of wipers arranged side by side, a wiper transferring slide in which said wipers are mounted, said slide being arranged for movement to bring either pair of wipers into operative relation to a shoe being lasted.

35 5. A right and left end lasting mechanism having, in combination, two pairs of wipers, a transversely movable wiper transferring slide in which the wipers are mounted, means for locking the slide against transfer- 40 ring movement when either of the pairs of wipers is in operative position, means for operating the pair of wipers which is in operative position, and means operated by continued movement of the wiper operating 45 mechanism in one direction to unlock the transferring slide and enable it to be moved to bring the inoperative pair of wipers into operative position.

50 6. A right and left toe lasting mechanism having, in combination, a wiper carrying head mounted to present at all times the same uppermost and the same end toward the shoe, a right and left pair of end embracing lasting wipers mounted side by side 55 in said head, one set of wipers being formed to wipe an upper into lasted position over the bottom of a right shoe toe, and the other set of wipers being formed to wipe an upper into position over the bottom of a left shoe toe, and means for operating said plates to last either a right or left shoe.

60 7. A right and left end lasting mechanism having, in combination, end embracing wipers having an edge contour adapted to 65 wipe into lasted position an upper over the

end of a last for one foot, end embracing wipers arranged at one side of the first wipers and in the same plane and having an edge contour adapted to wipe into lasted position an upper over the end of a last for 70 the opposite foot, a transferring slide carrying the wipers and by which the end embracing wipers for one foot may be moved laterally in a right line to a position where they will be out of the way of use of the 75 wipers for the other foot, and means whereby the said wipers for the other foot can be operated to do their work.

8. An end lasting mechanism having, in combination, two complete sets of end embracing plates arranged side by side, each set of wipers being mounted for advancing and turning movement to close and open relatively to a shoe end and having an edge contour differing from that of the other set, 85 a shoe end support, and means by which said end embracing plates and said support can be relatively moved to present the shoe bottom and the lower face of either set of wipers in suitable relation for the wipers 90 to wipe an upper into lasted position over the shoe bottom.

9. In a machine of the class described, an end lasting mechanism comprising two pairs of toe embracing plates arranged side by 95 side, each pair of plates completely embracing the toe and being mounted for combined advancing and turning movement to close and open relatively to a shoe end to wipe the shoe upper inwardly over the feather of a 100 welt sole innersole, the edges of said two pairs of plates being of different curvature to adapt them respectively to right and left shoe toes, and an operating means by which either pair of toe embracing plates may be 105 used upon the shoe for which they are adapted to the exclusion of the other pair.

10. An end lasting mechanism having, in combination, two complete pairs of end embracing wipers arranged side by side and 110 shaped respectively for right and left lasts of the same style, shoe positioning means, the said wipers being constructed and arranged for movement laterally of the shoe to bring either pair into operative relation to the 115 shoe toe on said positioning means, and an operating means for the two pairs of wipers by which either pair may be operated to wipe the upper over the last bottom.

11. End lasting mechanism having, in 120 combination, two complete sets of toe embracing plates arranged side by side, one set having a different edge contour from the other to adapt it to embrace and snugly fit a shape different from the shape which the 125 other fits, and operating means common to the two sets of wipers and arranged to impart to one set of wipers toe embracing movements while the other set remains stationary.

12. A right and left toe lasting mechanism having, in combination, two sets of wipers, mechanism for each set which when operated will produce advancing and closing movement of that set, a single operating lever, and means by which one set may be disconnected from the operating lever and the other set connected to the lever for operation thereby.

10 13. A right and left lasting machine having, in combination means for supporting a shoe, a toe lasting head adjustable relatively to the shoe support to adapt lasting instrumentalities to characteristics common to the 15 right and left shoes of a pair, two pairs of wipers mounted side by side on the toe lasting head, said pairs of wipers being respectively adapted to characteristics of right and left shoes and being adjustable into operative relation to the shoe support alternatively, and means for operating the wipers while they occupy operative position.

14. A right and left lasting mechanism having, in combination, two pairs of wipers arranged side by side, a transferring slide on which said wipers are mounted, operating mechanism for each pair of wipers for effecting combined advancing and turning movement of the wipers to close and advance over the shoe end to wipe the shoe upper inwardly over the innersole, a wiper operating rod, and means by which the operating mechanism for either pair of wipers may be connected to the rod by movement 35 of the transferring slide.

15. A machine of the class described having, in combination, a shoe support, an end-lasting head, a slide mounted in the head for movement transversely of a shoe on the 40 support, two sets of wipers mounted in the slide for advancing and closing movements, wiper operating mechanism common to the two sets of wipers, and means whereby either pair of wipers may be connected to the operating mechanism by transverse movement 45 of the slide.

16. In a machine of the class described, an end lasting head, a wiper transferring slide mounted in the head, two pairs of wipers 50 mounted in the transferring slide, mechanism for each pair of wipers whereby they may be advanced and closed over the shoe bottom, a pin carried by each advancing and closing mechanism, said lasting head 55 having a slot extending longitudinally of the shoe and adapted to be engaged by the pin belonging to the advancing and closing mechanism of that set of wipers which is

being operated to prevent lateral movement of the set during operation.

17. In a machine of the class described, an end lasting head, a slide mounted in said head, two sets of wipers mounted in the slide, advancing and closing mechanism for each set of wipers, oppositely directed forks on said mechanism, a longitudinally movable operating rod having a formation adapted to be engaged by one or the other of the forks as the slide is moved relatively to the rod.

18. In a machine of the class described, two pairs of end embracing wipers, a moving slide in which the wipers are mounted, an operating lever, means for connecting either pair of wipers to the operating lever when the slide is moved, means for locking the slide when either pair of wipers is in operative position, and means operated by movement of the operating lever beyond its normal movement for opening and closing the wipers for unlocking the moving slide to enable the pair of wipers which is in use to be moved out of operative position and the pair which is out of operative position to be moved into operative position.

19. An end lasting mechanism having, in combination, two pairs of end embracing wipers arranged in substantial parallelism, each pair having an edge contour adapted to wipe a shoe upper into lasted position over a last bottom, one pair of wipers having a contour differing from that of the other pair of wipers, the said pairs being movable to locate one pair of wipers out of operative position and the other pair in operative position, and means for operating either pair of wipers to do its work arranged to be disconnected from one pair of wipers and connected to the other pair when said other pair is located in operative position.

20. In a machine of the class described, two pairs of end embracing wipers, a movable slide in which the wipers are mounted, an operating lever, means for connecting either pair of wipers to the operating lever when the slide is moved, means for locking the slide when either pair of wipers is in operative position, and means for unlocking the slide to enable the pair of wipers which is in use to be moved out of operative position and the other pair to be moved into operative position.

In testimony whereof I have signed my name to this specification.

EVERETT W. VARNEY.

It is hereby certified that in Letters Patent No. 1,358,127, granted November 9, 1920, upon the application of Everett W. Varney, of Newton, Massachusetts, for an improvement in "Lasting-Machines," an error appears in the printed specification requiring correction as follows: Page 3, line 52, after the word "same," first occurrence, insert the word *side*; and that the said Letters Patent should be read with this correction therein that the same may conform to the record of the case in the Patent Office.

Signed and sealed this 25th day of January, A. D., 1921.

[SEAL.]

L. B. MANN,
Acting Commissioner of Patents.

Cl. 12—14.
